SPOON

Leslie W. Seibert, Jr., Northbrook, Ill., assignor to Ekco Products Company, Chicago, Ill., a corporation of Illinois

Application September 9, 1954, Serial No. 32,199

Term of patent 14 years

(Cl. D44—29)

FIG. 1.

FIG. 2.

FIG. 3.

FIG. 4.

Fig. 1 is a front elevational view of a spoon showing my new design.

Fig. 2 is a side elevation thereof.

Fig. 3 is an end elevational view thereof; and

Fig. 4 is a section taken on line 4—4 of Fig. 1.

The characteristic features of the present design reside in the specific angular bowl configuration in combination with a handle of V-shaped upwardly open channel formation throughout the length of said handle.

I claim:

The ornamental design for a spoon, as shown and described.
